UNITED STATES PATENT OFFICE.

ALLEN T. HOXTER, OF ATLANTA, NEW YORK, ASSIGNOR TO BOGGS MFG. CORP., OF ATLANTA, NEW YORK, A CORPORATION OF NEW YORK.

SORTING-MACHINE BELT.

Application filed June 24, 1922. Serial No. 570,616.

To all whom it may concern:

Be it known that I, ALLEN T. HOXTER, of Atlanta, in the county of Steuben and State of New York, have invented certain new and useful Improvements in Sorting-Machine Belts; and I do hereby declare the following to be a full, clear and exact description of the same, reference being had to the accompanying drawings forming a part of this specification and to the reference numerals marked thereon.

This invention relates to sorting or grading machines and more particularly to sorting belts for the same, one object of the invention being to provide a simple, efficient and durable belt having convenient means for detachably connecting the ends and adjusting the length thereof. Another object is the provision of a chain belt of the above description of a light flexible character easy to construct at a comparatively low cost, having meeting ends formed for conveniently detachable engagement with each other to facilitate application or removal of the chain or adjustment of its length to suit different operating conditions. To these and other ends the invention resides in certain improvements and combinations of parts all as will hereinafter be more fully described, the novel features being pointed out in the claims at the end of the specification.

In the drawings;

Figure 1 is a vertical longitudinal section through a sorting machine having the present invention applied thereto;

Figure 2 is an enlarged detailed view of a sorting chain embodying the present invention;

Figure 3 is a sectional view on the line 3^a—3^a of Figure 2.

Similar reference numerals throughout the several views indicate the same parts.

The invention is embodied in the present instance, by way of illustration, in a sorting belt of a machine for sorting or grading vegetables or other articles, such, for example, as potatoes, and Figure 1 shows a machine of this description comprising a substantially rectangular frame having side

boards 5 supported on legs 6 and united by a board 7 at one end adjacent which is provided a hopper 8 to receive the articles to be sorted. At the ends of the frame are rollers 9 and 10 rotatably journalled at their ends in the frame sides 5. The sorting belt indicated generally at 11 is supported for movement on these rollers, the roller 9 having an angular surface or being otherwise provided with means for engagement with the belt to drive the latter. Suitable means are provided for rotating roller 9 and a number of idle rollers 12 are preferably provided for supporting the upper or active run 13 of the belt, the lower run or side 14 of which may be allowed to sag loosely toward the floor to provide space between the upper and lower sides of the belt for any suitable means for collecting articles which by reason of their size pass through the upper run. Such articles as remain on the belt are discharged over the end of the latter, this machine being of a well known variety and type of construction the details of which require no further description.

The invention is embodied in the present instance in a sorting belt or chain shown as applied to a machine of the above description and of the general character described in Letters Patent to F. Boggs 1,032,375, dated July 16, 1912. This belt is in the form of a light flexible chain comprising a plurality of strips of wire 15 each formed to provide longitudinally thereof a series of loops 16 with intermediate connecting portions 17 between adjacent loops, the connecting portions of one strip being engaged in the loops of the adjacent strip to join adjacent strips for pivotal movement relatively to each other about axes extending transversely of the belt or chain. The loop portions 16 and intermediate connecting portions 17 are preferably spaced, as shown in Figure 2, to form openings 18 of a size and shape adapted to permit the passage therethrough of the articles of the grade which it is desired to have pass through the belt. This arrangement results in an advantageous staggering of the openings 18 in adjacent strips,

so that an article moving lengthwise relatively to the belt shortly encounters one of the openings. This result is preferably obtained by forming the strips in the approximate shape of a spiral coil as shown, which is easy to produce by simple forming means and has the further advantage in that it permits of the engagement of adjacent strips during manufacture or repair by rotating 10 and screwing the coils, so to speak into place. When adjacent coils have been thus assembled the terminals may be interlocked by a simple bending as at 19. This construction affords a free pivotal movement of 15 one strip on the other about an axis extending transversely of the belt and produces a light but strong and durable chain which cooperates advantageously with the supporting and driving rolls.

20 It has been found in practice to be desirable to provide means for detachably connecting the meeting ends of the chain to facilitate its application to and removal from a machine and to provide for the connection of one end of the chain with different selected strips adjacent the other end thereof for adjusting its length to different machines or to control the degree of tension. To this end means are provided for attachment 25 to the terminal strip 15 at one end of the chain, having hook-like parts for detachable engagement with loop portions of one of the strips 15 adjacent the other end of the chain, so that the meeting ends may 30 be conveniently fastened together, the tension of the chain serving to hold the parts in connection. This connecting means or member is, in the present instance, in the form of a wire strip 20, Figure 2, formed longitudinally thereof with a series of loop portions 35 21 generally similar to the loop portions 16 of the strips 15 and adapted for engagement with the connecting portions 17 of the terminal strip 15 at one end of the chain. The connecting member or strip 20 is formed at its opposite side and intermediate the loops 21 with open, hook-like loops 22 adapted for conveniently detachable engagement with the loop portions 16 of a strip 15 adjacent the other end of the chain. Connecting strip 20 may have its hooks 22 thus engaged with the terminal strip at the other end of the chain, or with the loop portions of a selected strip 15 spaced 50 at some distance from the opposite end of the chain, as found convenient for adjusting the length of the latter. Where it is found desirable to engage the connecting strip 20 with a strip 15 somewhat spaced from the opposite end of the chain, the free terminal strip or strips not in use may, if desired, be readily uncoiled or unscrewed and removed from the chain by a simple 55 operation, the attachment of the chain ends 60 being thus made by simply engaging hooks 65

22 with the loop portions of a selected strip, without having to effect engagement of the chain ends by coiling a strip 15 into place as would otherwise be necessary without a detachable connecting member of the character described. The connecting member may, of course, have various modifications in its details of construction, the present form being preferred as one which is readily constructed and convenient in operation as well as maintaining the uniform strength of the belt.

I claim as my invention:

1. A sorting belt comprising a plurality of wire strips each formed to provide longitudinally thereof a series of loops with intermediate connecting portions between adjacent loops, the connecting portions of one strip being engaged in the loops of the adjacent strip to join adjacent strips for pivotal movement about axes extending transversely of the belt with their respective loops in staggered relation, and a connecting strip formed to provide longitudinally thereof a series of loops engaged 80 with the terminal strip at one end of the belt and having hook-like portions intermediate said loops for detachable engagement with the terminal strip at the other end of the belt for detachably connecting 85 the belt ends together.

2. A sorting belt comprising a plurality of wire strips each formed to provide longitudinally thereof a series of spaced loops successive ones of which are arranged alternately on opposite sides of the strip for pivotal connection with complementary loops of an adjacent strip with the spaces between loops of adjacent strips in staggered relation, and a connecting member attached to the terminal strip at one end of the belt and provided with open hook portions for detachable engagement with the loops of a strip adjacent the other end of the belt for detachably connecting the belt ends 100 together.

3. A sorting chain comprising a plurality of wire strips each formed to provide longitudinally thereof a series of spaced loops successive ones of which are arranged alternately on opposite sides of the strip for pivotal connection with complementary loops of an adjacent strip with the spaces between loops of adjacent strips in staggered relation, and a connecting wire strip 115 formed to provide at one side thereof a series of loops for engagement with the loops of the terminal strip at one end of the chain and to provide at the other side thereof a series of open hooks for detachable engagement with the loops of a strip adjacent the other end of the chain for detachably and adjustably connecting the chain ends 120 together.

4. A sorting chain comprising a plurality 130

of wire strips each spirally coiled to provide on each side thereof a series of loops pivotally engaged with complementary loops of an adjacent strip, and a connecting wire strip formed with loops on one side thereof engaged with the loops of a strip at one end of the chain and with open hook por-

tions on the other side thereof for detachable engagement with the loops of a strip adjacent the other end of the chain for detachably and adjustably connecting the chain ends together. 10

ALLEN T. HOXTER.
